UNITED STATES PATENT OFFICE.

ANDREW J. SMITH, OF SPRINGFIELD, ILLINOIS, ASSIGNOR OF ONE-THIRD
TO HERBERT GRISWOLD, OF SAME PLACE.

KEY MECHANISM FOR MUSICAL INSTRUMENTS.

SPECIFICATION forming part of Letters Patent No. 633,915, dated September 26, 1899.

Application filed March 14, 1899. Serial No. 709,005. (No model.)

To all whom it may concern:

Be it known that I, ANDREW J. SMITH, a citizen of the United States, residing at Springfield, in the county of Sangamon and State of Illinois, have invented certain new and useful Improvements in Key Mechanism for Musical Instruments, of which the following is such a full, clear, and exact description as will enable others skilled in the art to which it app pertains to make and use my said invention.

My invention relates to musical instruments of that class—such as pianos, organs, &c.—which have keys which may be manipulated to produce various musical notes.

15 The purposes of my invention are to provide simple and effective means to prevent sticking of the keys and to provide means whereby the accumulation of dirt within the instrument may be avoided.

20 With these ends in view my invention consists in certain novel features of construction and combinations of parts shown in the annexed drawings, to which reference is hereby made, and hereinafter described, and pointed 25 out in the claim.

Referring to the drawings, Figure 1 is a side elevation of the complete mechanism. Fig. 2 is a top plan view of a part of the guide-rail carrying the guides or eyes in which the 30 guide-pins work. Fig. 3 is a vertical section through the guide-rail on the line 3 3 of Fig. 2. Fig. 4 is a vertical transverse section through one of the keys on the line 4 4 of Fig. 1. Fig. 5 is a horizontal transverse section through one of the guide-pins on the line 35 5 5 of Fig. 1, looking downward, and shows in top plan one of the eyes or guides in which the guide-pins work.

Similar letters of reference designate like 40 parts in all of the views.

In the drawings I have shown only one key, it being understood that there are a number of keys, all exactly alike and arranged side by side.

45 In order that the nature of my invention may be clearly understood, I will state that prior to my invention of the improvements herein described the common practice has been to guide the keys by means of vertical 50 guide-pins immovably secured to a rail un-

derlying the keys near the front end thereof, the upwardly-projecting ends of the pin fitting in longitudinal felt-lined mortises in the lower part of the keys. The keys being commonly made of pine or other light and porous wood, it is found in practice that when exposed to moisture the wood swells, thereby contracting the mortises in the keys to such extent as to cause the pins to bind in the mortises, and thereby prevent free movement of 60 the keys. One of the main purposes of my invention is to overcome this difficulty, and I accomplish this result by securing the guide-pins rigidly on the keys and forming the eyes in which the guide-pins work on a sill or rail 65 of metal or other non-porous or non-absorbent material which will not swell when exposed to moisture.

The guide-rail A, the center rail B, and the rear rail D are supported on and suitably secured to two or more sills C, transverse to the instrument in which the key mechanism is employed. Vertical pins B', one for each key, are secured at suitable distances apart on the center rail B. A felt washer B² surrounds 75 each of the pins B'. A longitudinal felt cushion D' is cemented or otherwise secured on the upper surface of the rear rail D.

The box-shaped guide-rail A is made of metal or hard rubber or indurated fiber or 80 other material which will not swell to a deleterious extent when exposed to moisture. The rail A being boxed-shaped and foraminated as shown, combines attractive appearance with lightness and strength, and by 85 reason of its form may be of the necessary depth without being unduly bulky or heavy.

On the rail A are a series of suitably-placed bosses A', one boss for each key of the mechanism. Each of the bosses A' is pierced by 90 a rectangular opening or eye a, in which the guide-pins on the keys move, as hereinafter set forth. Linings a', of felt or other suitable yielding and sound-deadening material, are cemented or otherwise suitably secured to the 95 side walls of the openings a.

In order to prevent the accumulation of dirt on the rail A, it is made foraminous, as clearly shown in Fig. 2. The precise form of the openings in the rail is immaterial, and 100

they may be made of any form adapted to lighten the rail without unduly impairing its strength.

The key proper, E, is preferably of pine or other light wood. A finger plate E', of ivory or other suitable material, is suitably secured to the key E.

The guide-pin E² is preferably in cross-section elliptical in form and for a part of its length is preferably screw-threaded, as at e, and screws into the key E.

The pin E² is made of elliptical cross-section, as described, in order that when the felt linings a' in the eyes a become worn to such extent as to permit undue lateral motion of the pins in the eyes the pins may be turned slightly, so as to compensate for the wear, and thus obviate the necessity for replacement of the felt lining a'.

I do not confine my claim to a pin of elliptical cross-section, since it is obvious that pins of any other form of which the cross-section is a curve having a major and a minor axis may be used. Neither do I confine my claim to a screw-threaded pin, since it is obvious that other means may be employed for turnably connecting the pin with the key. It is essential only that the pin shall be turnable and that it shall be of such form that when turned the transverse measurement of the pin shall properly correspond to the transverse distance across the eye in which the pin slides.

A felt washer E³ surrounds the pin E² and

is secured to the under side of the key E. When the key is depressed, the washer abuts against the upper surface of the boss A'.

An adjusting-pin F screws into the key E. The key E is pierced between its extremities by a vertical slot e', (shown in dotted lines Fig. 1,) through which the pin B' passes. The slot e' is longer at the top than at the bottom in order that the key may oscillate freely on the washer B² without striking against the pin.

A suitable number of suitably-placed weights E⁴, of lead or other heavy material, serve to balance the key in such manner as to make it properly responsive to the touch of the person performing on the instrument.

Having fully described my invention, what I claim as new, and desire to secure by Letters Patent, is—

In key mechanism for musical instruments, the herein-described box-shaped foraminated guide-rail provided with bosses having eyes bushed with sound-deadening material, in combination with oscillative keys and oval pins on said keys registering with and turnable for transverse adjustment in the eyes of said guide-rail, as set forth.

In witness whereof I have hereunto subscribed my name, at Springfield, Illinois, this 8th day of March, 1899.

ANDREW J. SMITH.
